UNITED STATES PATENT OFFICE.

ARCHIE E. BRADY, OF HOUSTON, TEXAS, ASSIGNOR OF ONE-HALF TO JAMES P. ROGERS,
OF HARRIS COUNTY, TEXAS.

AUTOMATIC FISHING TOOL.

Application filed April 18, 1922, Serial No. 555,079. Renewed October 19, 1923.

To all whom it may concern:

Be it known that I, ARCHIE E. BRADY, a citizen of the United States, residing at Houston, in the county of Harris and State 5 of Texas, have invented certain new and useful Improvements in an Automatic Fishing Tool, of which the following is a specification.

This invention relates to new and useful 10 improvements in an automatic fishing tool.

One object of the invention is to provide a tool of the character described which is adapted to be attached to a string of pipe to be let down into a well bore, and which is 15 provided for the purpose of picking up objects at the bottom of the bore. In well drilling, bits, cones and other similar objects are often dropped in the bore and it is very difficult to recover them. However they 20 must be removed before drilling can proceed, and it is the object of this invention to provide an apparatus which may be attached to the lower end of the drill stem or other string of pipe and let down into the bore 25 to engage with and recover such objects as may lie on the bottom of the bore.

With the above and other objects in view the invention has particular relation to certain novel features of construction, operation 30 and arrangement of parts, an example of which is given in this specification and illustrated in the accompanying drawings, wherein:—

Figure 1 shows an enlarged vertical section view of the fishing tool.

Figures 2 and 3 show, respectively, a vertical sectional view, and an inside view of the grappling hooks employed.

Figure 4 shows a bottom plan view of the 40 anchor block employed, showing the locking ring associated therewith, and

Figures 5 and 6 show transverse sectional views taken on the respective lines 5—5 and 6—6 of Figure 1.

Referring now more particularly to the drawings, wherein like numerals of reference 45 designate similar parts in each of the figures, the numeral 1 designates the cas-

ing which is set in the well bore. The numeral 2 designates the drill stem or other 50 string of pipe to the lower end of which the fishing tool is attached. Threaded into the lower end of this drill stem there is a cylindrical anchor block 3 having a central bore 4, and the vertical water passageways, 55 located out near the periphery of the block as shown and whose upper ends may be closed by the plugs 6.

The underside of the block 3 has the 60 depending lugs 7, 7, arranged in pairs on opposite sides of the respective passageways 5, and pivoted between the lugs of the 65 respective pairs, and depending therefrom are the grappling hooks 8, arranged in oppositely disposed pairs, the hooks of each pair being connected by the strong coil springs as 9, as illustrated in Figure 1. The shanks of these hooks are substantially tubular and each has the inside vertical inside slot 10 at its lower end, and the outside slot 11 at 70 its upper end, as illustrated in Figures 2 and 3. Said shanks also have the aligned vertical slots 12 whose lower ends are turned inwardly forming the recesses 13.

Working within the shanks of said grappling hooks are the push rods 14, whose lower ends are inwardly curved and work through the slots 10 of said shanks, and whose upper ends are formed into fingers 15 which are aligned with and adapted to work 80 up through the water passageways 5. Within the shanks of the respective grappling hooks are the strong pull springs 16 whose lower ends are connected to the lateral ears 17 carried by the corresponding push rods 85 14 and whose upper ends are attached to one of the corresponding lugs 7. Each push rod has a transverse bearing pin 18 projecting each way therefrom and whose ends work in the respective aligned slots 12.

Loosely surrounding the anchor block 3 there is a locking ring 19, which is supported upon the dogs 20. These dogs are pivoted in the lower ends of the recesses 21 in the sides of said block. Secured to the 95 outer sides of the upper ends of the push

rods 14 and working through the outside slots 11 are the triggers 22 which are aligned underneath the respective dogs 20.

The push rods 14 are held in their lower position by seating bearing pins 18 in the recesses 13, as shown in Figure 1 and the springs 16 are thereby held under tension.

A central trip rod 23 is provided, whose upper end is formed with a head 24 which works in cylindrical bore 4. When the apparatus is set for lowering into a well bore this trip rod projects down below the grappling hooks. Fastened on this rod there is a collar 25 to which the inner ends of the links 26 are pivoted and the outer ends of these links are pivoted to the respective grappling hooks.

The device is assembled as shown in Figure 1 and is attached to the lower end of the string 2 and let down to the bottom of the bore. When the lower end of the trip rod 23 reaches the object to be fished out of the bore its descent is stopped and as the device moves on down the links 26, acting as toggle levers will force the grappling hooks apart, and while in this position they move on down to the bottom of the bore before the collar 25 passes above the plane of the points of attachment of the links to the grappling hooks, and when said collar has passed above said plane the springs 9 will suddenly act to pull the grappling hooks together and engage them under the object to be removed, the links 26 assuming the position shown in dotted lines in Figure 1. Thereupon said object will strike against the inwardly turned ends of the push rods 14, and force said ends outwardly, unseating the pins 18 from the recesses 13, and the springs 16 will immediately act to suddenly project said rods upwardly, and cause the fingers 15 to unseat the plugs 6, thus opening the water courses 5. At the same time the triggers 22 will strike against the dogs 20 and release them from underneath the ring 19 and seat them in the recesses 21. The ring 19 will then drop around the grappling hooks and hold them locked around the object to be recovered. The object within the grappling hooks will hold their lower ends apart somewhat, causing them to diverge outwardly, and the ring will wedge thereover and be prevented from passing on entirely over said hooks.

It is to be noted that a pump at the surface of the ground is connected to the stem 2 and while the upper ends of the water passageways 5 are plugged up said pump will not operate as the fluid can not pass from the stem, but as soon as said plugs 6 are unseated the pump will then work and this will indicate that the object to be fished out has been caught within the grappling hooks.

Should the device fail to engage with the

object sought to be recovered, that is should the grappling hooks open and then close above said object the push rods 10 would not be released and the plugs 6 would not be unseated and this would be indicated by the failure of the pump to work. In that event the tool should be elevated slightly in the bore, and the pressure of the fluid in the stem 2 will operate against the plunger 24 and force the trip stem 23 downwardly into its original position and set the device for another operation.

What I claim is:—

1. The combination with a string of pipe, of an anchor, grappling members depending from the anchor, and movable into open and closed position, means normally holding said members in closed position, a device for actuating said members into open position and then releasing them to the influence of said closing means, and a releasably mounted locking ring disposed when released to lock around and secure said grappling members in position.

2. The combination with a string of pipe, of an anchor attached to and closing the lower end thereof and provided with a water passageway, means normally blocking said passageway, grappling members depending from said anchor and arranged to open and close, a device arranged to open said members and then release them, means for closing said members when so released, a push rod aligned with said passageway, means locking the same against actuation and a yieldable member attached to said rod and disposed to actuate the same through said passageway to remove said blocking means, when said locking means is released.

3. The combination with a string of pipe, of an anchor attached thereto, grappling members depending from said anchor and arranged to open and close, a device arranged to open said members and then release them, means for closing said members when so released, a locking ring, releasable supporting means whereby said ring is supported above the grappling members and means provided to automatically release said supporting means from said ring thereby permitting the ring to descend around said grappling members.

4. The combination with a string of pipe of an anchor attached to and normally closing the lower end thereof and provided with water passageways, means normally blocking said passageways, grappling members depending from said anchor and arranged to open and close, a device arranged to open said members and then release them, means for closing said members when so released, push rods aligned with said passageways, means normally locking said rods against actuation, yieldable members disposed to actuate said rods, when released, through

said passageways to remove said blocking means, a locking ring, releasable means supporting said locking ring above said grappling members and means carried by said rods and operating to release said supporting means, when the rods are actuated, thereby permitting said ring to drop around said grappling members.

In testimony whereof I have signed my name to this specification in the presence of ¹⁰ two subscribing witnesses.

ARCHIE E. BRADY.
